His Attorney.

UNITED STATES PATENT OFFICE.

EDWARD W. THOMPSON, OF LOWELL, MASSACHUSETTS, ASSIGNOR OF TWO-
THIRDS TO JAMES W. BENNETT AND ALBERT M. MOORE, BOTH OF
SAME PLACE.

TAG.

SPECIFICATION forming part of Letters Patent No. 271,378, dated January 30, 1883.

Application filed October 20, 1882. (No model.)

To all whom it may concern:

Be it known that I, EDWARD W. THOMPSON, a citizen of the United States, residing at Lowell, in the county of Middlesex and 5 Commonwealth of Massachusetts, have invented certain new and useful Improvements in Tags, of which the following is a specification.

My invention relates more particularly to the wooden tags commonly used in the postal service as direction-labels on sacks containing newspaper-mail, and to means of readily attaching said tags to and detaching said tags from said sacks.

In the accompanying drawings, Figure 1 is 15 an isometric view of such a tag with my improvement attached thereto. Fig. 2 is a side elevation of the same, the jaws being separated by a cord. Fig. 3 is a vertical central cross-section of the upper part of the jaws.

20 A is the upper part of a wooden tag of the usual shape, except as modified to suit my improvement, as described below. These tags are provided with a hole ordinarily, through which a piece of stout cord is passed, and the 25 tag is secured to a sack by tying said cord around the "puckering-string" of said sack. It is customary for postal clerks and drivers of mail-wagons to haul and lift these sacks by grasping the tag, and the knot in the cord 30 thereby becomes so hard that the knot is cut to save time, thus causing a great waste of cord. To save time and cord I apply my device to the tag. The diagonally-opposite corners of the tag are cut away, as shown in 35 Figs. 1 and 2, and springs or spring-jaws B B' are riveted to the tag, so as to be flush with the edges and faces of said tag, by means of rivets F, which extend through the tag and both springs, near the lower ends of said

40 springs, the parts of the springs in which the rivets are placed being preferably as wide as the tags are thick. The upper ends of the springs B B' are formed into jaws b b', respectively, long enough to lap by each other 45 and to enter notches d d' in the tag. The jaws are cut or rounded in at e to contain the cord, and are beveled on top down toward their points, so that a cord pressed down upon the top of the jaws will force them outward 50 and apart and allow the cord to enter the slot e, cut vertically in the top of the tag. With

these tags no cord is required, but the tag is applied directly to the puckering-string of the sack by pushing the jaws against said string. The tag is removed from the sack by 55 placing an adjacent part of the puckering-string x on the top of the jaws and forcing it into the slot e, when the loop thus formed in the puckering-string can readily be drawn through the slot. To avoid wear on the puckering-string x, the sharp edges of the jaws are rounded, as shown in Fig. 3. The corners not cut away at the top of the tag afford a substantial side support for the jaws and prevent the stiff puckering-string from moving 60 the jaws unequally and from moving the jaws apart laterally. The jaws should be made of spring-steel of such a quality and strength as to resist any strain tending to bend or break them; but it will be seen that if one jaw were 65 broken the other would still be operative, although it is deemed advisable to use two jaws.

I claim as my invention—

1. The tag A, provided with the slot e, and 70 having one or more corners cut away, as described, in combination with a spring-jaw, B, or jaws B B', attached to said tag, substantially as and for the purpose specified.

2. The tag A, provided with the slot e, and 75 having one or more corners cut away, as described, in combination with one or more spring-jaws, B B', having beveled upper surfaces and being attached to said tag, as and for the purpose specified.

3. The tag A, provided with the slot e, and 80 having one or more corners cut away, as described, in combination with one or more spring-jaws, B B', beveled on the upper surface and rounded in on the under surface and attached to said tag, as and for the purpose 85 specified.

4. The combination of the tag A, having a slot, e, and having its diagonally-opposite corners cut away, as described, and a pair of overlapping spring-jaws, B B', said jaws being 90 oppositely beveled on their upper surfaces, and being attached to said tag, as and for the purpose specified.

EDWARD W. THOMPSON.
